UNITED STATES PATENT OFFICE.

THOMAS DIXON, OF WASHINGTON, DISTRICT OF COLUMBIA, ASSIGNOR TO WASHINGTON STEEL & ORDNANCE COMPANY, OF WASHINGTON, DISTRICT OF COLUMBIA, A CORPORATION OF WEST VIRGINIA.

MEANS FOR SECURING CAPS TO PROJECTILES.

1,027,243.

Specification of Letters Patent.

Patented May 21, 1912.

Application filed March 25, 1912. Serial No. 686,047.

To all whom it may concern:

Be it known that I, THOMAS DIXON, a citizen of the United States, residing at Washington, in the District of Columbia, have 5 invented certain new and useful Improvements in Means for Securing Caps to Projectiles; and I do hereby declare the following to be a full, clear, and exact description of the invention, such as will enable others 10 skilled in the art to which it appertains to make and use the same.

This invention relates to devices for securing caps to shells, and has for its object to produce a means which will hold the cap 15 at all times in tight contact with the shell, and thereby operate more efficiently in action than those which have been heretofore proposed.

As is well known, it is difficult to maintain 20 the ordinary caps in tight contact with the projectile, because during shipment, as well as in handling aboard ship, they are subjected to knocks and strains that are liable to loosen them. It is further well known 25 when a cap once becomes loose, not only is its axis liable to be out of alinement with the axis of the projectile during flight, but this defect is liable to be accentuated owing to the fact that its inertia, while the shell 30 is rotating, tends to prevent it from revolving with the shell body, and therefore acts to further loosen it, and to increase the inaccuracy of fire.

In order to keep caps in tight contact with 35 the projectile, it has been heretofore proposed to provide the cap and shell with registering grooves and to force metal into said grooves to lock the cap. But, not only do these grooves tend to weaken the shell, 40 but in practice, it has been found that a few hard knocks on the tip of such caps are apt to loosen them, and when they are once loosened, the metal being cold, there is no way to tighten them. The same remarks 45 apply to those caps in which the metal is swaged into a groove on the shell. It has been further proposed to tighten caps by heating their skirts, driving pins between the same and the projectiles, and allowing 50 the metal to cool; but such heating is liable to damage the penetrative powers of the shells by drawing their temper. An additional means for securing the cap to the

projectile proposed heretofore, involves raised and sunken portions of metal on the 55 shell and cap, but is equally objectionable owing to its expense, as well as owing to the decreased penetration due to the said raised portion. It has even been proposed to secure the cap to the shell with the aid of 60 screw devices, but the screws have pointed toward the base of the projectile, so that upon tightening the same, the cap would not tend to be drawn over the pointed end of projectile, and therefore, such devices have 65 failed to secure the desired tight contact between the cap and projectile and resistance to loosening strains, as in the previous cases.

I avoid all of the above objections by the 70 means constituting my invention, as will now be more fully hereinafter disclosed and particularly pointed out in the claims.

Referring to the accompanying drawings forming a part of this specification in which like numerals designate like parts in all the 75 views:—Figure 1 is an elevational view partly in section of the forward portion of a shell provided with a cap equipped with my invention; Fig. 2 is a plan view of the parts shown in Fig. 1 with the fastening 80 means omitted; and, Fig. 3 is an enlarged detail sectional view of my fastening means, showing a slightly modified form of lock.

1 indicates the body of the forward portion of the shell; 2 the well known cap fitting over the same; 3 an orifice bored through the straight portion of the cap inclined to the axis of the shell and cap, when the parts are in place, and slanting toward the point of said cap and shell, as illustrated. The said orifice 3 is further screw-threaded, as best indicated in Fig. 3. In addition to the orifice 3, I form a pocket 4 in the forward portion of the shell whose axis coincides with the axis of the orifice 90 3, and which is provided with an abrupt bottom 5, as is also best indicated in Fig. 3.

6 represents a portion of a screw-threaded bolt adapted to fit the orifice 3 and the pocket 4, and to lie flush with, or slightly 100 beneath, the surface 7 of the cap 2. When the said bolt 6 is caused to lie slightly beneath the surface 7, as indicated in Fig. 3, I may force the metal 8 surrounding the orifice 3 over the rim of said bolt 6 in order 105 to firmly lock the same in place. But, in

ordinary cases, it is found, as indicated in Fig. 1, that the bolt 6 holds the parts sufficiently tight to render this locking means unnecessary.

5 The operation of my invention will be clear from the foregoing, but may be briefly summarized as follows:—The cap 2 is placed over the shell 1, and by a jig, or other suitable means, the orifice 3 and pocket 4 are formed in the cap and shell, respectively, whereupon a bolt such as 9, Fig. 1, is screwed into said orifice, as illustrated, and cut off or otherwise severed, so that its extreme outer end will either lie even with 10 the surface 7 of the cap, as shown in Fig. 1, or slightly beneath the same, as shown in Fig. 3. In order that the said outer end may lie slightly beneath the surface, it can be gouged out, or the bolt itself can be 15 weakened so as to break off a portion 6 of just the right length to occupy the position shown in said Fig. 3. In all cases the outer head of the bolt 9 is removed when such bolts are employed. In some cases, 20 however, a bolt, such as 6, may be employed in the first instance, and provided with a slot in its outer end for engagement with a screw-driving tool.

The important feature of my invention 30 resides in the fact that the orifice 3 and pocket 4 have their axes inclined to the axes of the cap and shell, and point in a forward direction. The effect of this disposition of parts is to cause the cap to be tightly drawn 35 over the surface of the shell, while applying the bolt 6, and to be thereafter tightly and firmly held against said surface at all times. Further, by providing the abrupt flat bottom 5 to the pocket 4, against which the 40 extreme end of the bolt 6 abuts, it is found to be impossible to loosen this cap by any ordinary knocks or strains to which the cap is usually subjected. It, therefore, follows that by the simple expedient above disclosed, 45 I avoid all the objections which have been

inseparable from the fastening means heretofore proposed.

It is obvious that those skilled in the art may vary the details of construction and the arrangement of parts without departing 50 from the spirit of my invention, and therefore I do not wish to be limited to the above disclosure except as may be required by the claims.

What I claim is:—

1. The combination of a projectile provided with a pocket whose axis extends toward the point of and is inclined to the longitudinal axis of said projectile; a cap provided with an orifice whose axis coincides with the axis of said pocket; and a fastening means adapted to hold said cap in tight contact with said projectile secured in said orifice and pocket, substantially as described. 55

2. The combination of a projectile provided with a forwardly inclined pocket; a cap provided with a screw-threaded orifice registering with said pocket; and a screw-threaded member fitting said orifice and 70 pocket adapted to draw said cap toward said projectile and to firmly hold the same in tight contact therewith, substantially as described. 85

3. The combination of a projectile provided with a plurality of partially open, forwardly inclined pockets extending beneath its outer surface; a cap having a plurality of inclined screw-threaded orifices registering with said pockets; and screw-threaded plug members fitting said orifices and pockets adapted to draw and hold said cap in tight contact with said surface, substantially as described. 75 80

In testimony whereof, I affix my signature, in presence of two witnesses.

THOMAS DIXON.
